UNITED STATES PATENT OFFICE.

JOHN LEVANDOFSKY, OF BUCHTEL, OHIO.

ELECTRIC-WIRE CLEAT.

Application filed March 22, 1923. Serial No. 626,742.

To all whom it may concern:

Be it known that I, JOHN LEVANDOFSKY, a citizen of the United States, residing at Buchtel, in the county of Athens and State 5 of Ohio, have invented certain new and useful Improvements in Electric-Wire Cleats, of which the following is a specification.

My invention relates to devices for holding and insulating electric wires and has 10 particular reference to those devices generally known as cleats.

An important object of the invention is to provide a device of this character so constructed that one of the wires may be removed, without disturbing the other wires 15 held by the cleat.

Another object of the invention is the provision of a cleat in which the means for holding the device in clamping position with 20 relation to the electric wires is separate and distinct from the means securing the cleat to its support.

A further object of the invention is to provide a device of this character, which 25 will be easy to operate, compact in form, strong and durable.

Other objects and advantages of the invention will be apparent during the course 30 of the following description.

In the accompanying drawings forming a part of this specification, and in which like numerals are employed to designate like parts throughout the same,

Figure 1 is a perspective view of a device 35 embodying my invention,

Figure 2 is a top plan view of the cleat showing two electric wires held by the device,

Figure 3 is a central longitudinal sectional view of the device, taken on line 3—3 40 of Figure 2, with the open positions shown in dotted lines,

Figure 4 is a transverse section taken on line 4—4 of Figure 3, and,

Figure 5 is a detail elevation of the clamping jaw,

In the drawings, wherein for the purpose of illustration is shown a preferred form of my invention, the numeral 10 designates the body or base portion formed of insulating material and having cut-out portions 11 formed so as to leave an upstanding portion 12 in substantially the middle of the body portion 10. Ribs 13 extend outwardly from the upstanding member 12, one on each side and centrally thereof, and

project into the cut-out portions 11. These ribs are preferably integral with the body portion 11, and member 12. A section taken through the member 12 and the ribs 13 60 would be in the shape of a cross, the member 12 being the vertical arms of the cross, and the ribs 13 forming the horizontal arms. Transverse openings 14 extend through the ribs 13.

Jaws 15, also formed of insulating material, fit into the cut-out portions 11 and have grooves 16 to receive the ribs 13. Transverse openings 17 in the jaws align with the openings 14 in the ribs and a pin 18 extends through the openings 14 and serves to pivotally connect the jaws to the ribs. The inner ends of the jaws are rounded as at 19, so as to allow pivotal movement, and the inner faces of the grooves 70 are bevelled, as at 20, for the same purpose.

The contacting faces of the body portion and jaws are formed with grooves 21, transversely corrugated, as at 22, and when the device is in its operative position, the 80 grooves will form passages to receive the electrical wires 23, the corrugations 22 serving to prevent the wires from slipping.

A substantially U-shaped spring member 24 surrounds the cleat on three sides and is secured to the bottom or rear side of the body portion 10. The portion 10 is preferably longitudinally grooved as at 25 so that the spring member 24 will lie flush with the surface of the base 10.

The spring member 24 is formed from one piece of metal and only secured to the rear or bottom of the base 10. It is then bent at the ends of the base and extends along the opposite ends of the cleat. At its extremities the spring member is formed with rolls or beads 26 which extend over the top faces of the jaws and serves to hold said jaws in their closed positions.

Notches 27 are formed in the jaws 15, and have slanting faces 28 which guide the beads 26 out of the way of the jaws when they are being closed.

A transverse opening 29 extends through the body portion 10, and the spring member 24, and is adapted to receive a screw or bolt 30. This screw secures the device to the wall, ceiling or other support 31.

In operation the device is secured to a wall by the screw 30. The spring member is pushed aside by bearing on the beads 26, and the jaws may then be opened for inserting

the wires 23. In closing the jaws it is not necessary to bother with the spring clip 24 as the slanting face of the notch 27 will guide the spring member out of the way and when the jaws are completely closed, the beads 26 will project over the top of said jaws and serve to lock the jaws in their closed position.

It can readily be seen that by this construction it is possible to remove either wire or insert new wires without disturbing the other wire. It is also obvious that in removing or inserting wires, it is not necessary to disturb the securing screw 30, which is usual in the devices now on the market.

It is to be understood that the form of my invention herewith shown and described is to be taken as a preferred example of the same, and that various changes in the shape, size, and arrangement of parts may be resorted to without departing from the spirit of my invention or the scope of the subjoined claims.

Having thus described my invention, I claim:

- 25 1. In a wiring cleat, a base, jaws pivoted to the base, and spring clips adapted to retain the jaws in their closed position whereby either jaw may be operated independently of the other.
- 30 2. In a wire cleat, a base, means whereby the base may be secured to a support, a pair of jaws pivoted near their inner ends to the base, and adapted to be swung toward and away from the base in a plane perpendicular to the base, the wires being held between the jaws and the base and extending perpen-

dicular to the plane of movement of the jaws, and elements engaging the base and the outer end of the jaws to hold the jaws in the closed position, said elements being free from engagement with the wires.

3. In a wiring cleat, a base having a cut-out portion, a rib formed in the cut-out portion, a jaw adapted to fit in the cut-out portion and having a groove to receive the rib, a pivot element connecting the jaw and the rib, and means to retain the jaw in its closed position.

4. In a wiring cleat, a base having cut-out portions, means for securing the base to a support, ribs formed in the cut-out portions, jaws adapted to fit in the cut-out portions and having grooves to receive the ribs, pivot elements connecting the jaws to the ribs, and spring clips to retain the jaws in their closed position, whereby the jaws may be operated independently of each other and of the securing means.

5. In a wiring cleat, a base having cut-out portions, ribs formed in said cut-out portions, jaws having grooves to receive said ribs and pivoted thereto and having notches with slanting faces, and spring members secured to the base and having rolled ends to engage the slanting faces of the notches and be forced outwardly thereby in order to permit the jaws to reach their closed position, said rolled ends serving to lock the jaws in their closed position.

In testimony whereof I affix my signature.

JOHN LEVANDOFSKY.
